WILLIAM H. CLENDINEN, OF BALTIMORE, MARYLAND.

Design No. 3,948, dated April 5, 1870.

DESIGN FOR ORNAMENTAL LETTERS.

The Schedule referred to in these Letters Patent and making part of the same.

To all whom it may concern:

Be it known that I, WILLIAM H. CLENDINEN, of the city of Baltimore, in the county of Baltimore and State of Maryland, have originated and designed a new Pattern for Molded India Rubber Ornamental Letters and Numbers, of which the following is a description, reference being had to the accompanying drawing making part of this specification.

These letters and numbers will be of different sizes, and made to fasten on wood and other material with cement, or by having holes through them, as seen in the drawing, for small pins, the heads to show as little

as possible. These letters and numbers are to be solid or hollow, and nicely ornamented.

Claim.

What I claim as my invention, and desire to secure by Letters Patent, is—

The design for the molded India rubber letters and numbers, or their equivalents, substantially as shown.

WM. H. CLENDINEN.
